UNITED STATES PATENT OFFICE

LESTER T. LLOYD, OF CHICAGO, ILLINOIS, ASSIGNOR TO W. G. LLOYD COMPANY, OF CHICAGO, ILLINOIS, A CORPORATION OF ILLINOIS

LOOSE-LEAF BINDER

Application filed June 17, 1929. Serial No. 371,594.

This invention relates particularly to loose-leaf binders; and the primary object is to provide improved extension means for chain-posts in binders of the type in which only one of the clamping-members is equipped with take-up mechanism.

The invention is illustrated in a preferred embodiment in the accompanying drawing, in which—

10 Fig. 1 is a sectional view of a binder embodying the invention; Fig. 2, a broken sectional view taken as indicated at line 2 of Fig. 1; Fig. 3, a similar sectional view illustrating a modification; Fig. 4, an elevational view of a member which, in Fig. 3 is shown in section housed within a hollow clamping-member; and Fig. 5, a partly sectional view of one of the rotary connectors shown in Fig. 1.

20 Referring to Figs. 1, 2 and 3, A and A' designate the clamping-members of a loose-leaf binder which may, if desired, be equipped with cover-sections; B, B', flexible posts (chain-posts) connecting the clamping-members; and C, take-up mechanism housed within the clamping-member A', said mechanism comprising nuts 1 mounted on a right and left threaded rod 2 which is journaled against endwise movement within the clamping-member A'.

25 The clamping-member A' is equipped at its inner side with guides 3 about which the flexible posts extend, the ends of the flexible posts which are housed within the clamping-member being connected with the nuts 1 by means of pins 4.

The end-links of the flexible posts are designated 5. They are provided with reduced threaded extensions 5^a.

30 In accordance with the present invention, the clamping-member A, which has secured therein blocks 6, is equipped with rotatable connectors, or screw devices 7. Ordinarily, before extensions are applied to the flexible posts, the threaded studs 5^a of the terminal links of the chains are connected with the nuts 7. When the binder has been filled to a point requiring extension to be made, extension post-sections 8 are introduced. This is ac- 35 complished by disconnecting the terminal

links 5 from the nuts 7 and inserting the post-sections in the manner illustrated in Fig. 1.

Each of the screw-elements 7, in the illustration given, comprises an internally threaded sleeve-portion 7^a, an angular shank-portion 7^b, and a flange 7^c. A bore 9 extends through the block 6 and affords a bearing in which the member 7 is journaled and housed. The bore 9 is provided with an enlarged or countersunk portion 9^a, the bottom of which 60 affords a shoulder upon which the flange 7^c bears. A thick washer, or spacing ring, 10 is interposed between the flange 7^c and the outer wall 11 of the clamping-member A. A circular opening 11^a, co-axial with the bore 9, 65 is provided to enable a key to be inserted, the key receiving the angular shank 7^b and serving as a means for rotating the member 7.

70 It will be understood that the member 7 and the spacing-rings 10 may be entered in the chambers with which the blocks 6 are provided, and the blocks may then be inserted in the clamping-member A and secured therein, as by means of pins 12 (Fig. 2). Thus, the spacing-washer 10 is confined between the 75 wall 11 and the flange 7^c, and, accordingly, the member 7 is properly swiveled, or journaled, in its housing within the hollow clamping-member A.

75 The post-sections 8 are provided at one 80 end with a reduced threaded stud 8^a and at the other end with a threaded socket 8^b. Portions 8^a correspond with the portions 5^a of the terminal links 5, and the threaded 85 sockets 8^b correspond with the threaded sockets of the member 7.

One or more extension-sections may be connected with each flexible post, as desired.

80 In the modification shown in Figs. 3 and 4, 6^a designates a housing-member which may be used as a substitute for the block 6. This comprises a U-shape member 6^b and a barrel, or tubular member, 6^c. The tubular member 6^c is provided with a reduced lower end which extends through the opening in the lower 95 portion of the U-shaped member 6^b. The tubular post 6^c is provided with a countersunk bore in which is journaled a screw element 13 which comprises a reduced threaded portion 13^a, an angular shank-portion 13^b, 100

and an interposed flange 13^a. A thick washer 14 is interposed between the flange 13^a and the opposed wall of the clamping-member A. A double socketed post-section 15 has one end connected with the externally threaded portion 13^a of the screw element 13. The other internally threaded socket may connect with the threaded stud 5^a of the terminal link 5 of the chain-post. As shown more clearly in Fig. 3, the bearing 6^a is provided with a reduced lower end which extends through the lower wall of the U-shaped member 6^a.

Binders are now upon the market in which the terminal links 5 are provided with threaded studs; hence, it is preferred to employ the form of connecting-member designated 7. Use of the substitute connecting-member 13 requires either the use of a special extension-section of the form shown in Fig. 3, that is, one having the sockets at both ends; or, if the arrangement shown in Fig. 1 is to be reversed, the terminal link of the chain-post should be provided with an internally threaded socket instead of the externally threaded stud illustrated in Fig. 1.

It will be noted that the threaded rotary connector is, in each construction, housed within a suitable block, or journal-member, located within the tubular clamping-member, and the rotary connector is accessible by means of a key working through a perforation in the outer wall of the clamping-member. This enables the chain-post to be readily disconnected from the clamping-member A and extension-sections to be introduced with great facility.

The foregoing detailed description has been given for clearness of understanding only, and no unnecessary limitations should be understood therefrom, but the appended claims should be construed as broadly as permissible, in view of the prior art.

What I regard as new, and desire to secure by Letters Patent, is:

1. In combination in a binder, a hollow clamping-member having take-up mechanism mounted therein and having post-guides at its inner wall, flexible chain-posts having portions within said clamping-member connected with said take-up mechanism and having portions extending through said guides and equipped at their free extremities with threaded members; and a companion clamping-member having threaded rotary connectors journalled and confined therein and adapted for connection with said chain-posts, said connectors having key-engaging ends, and said last-mentioned clamping-member having key-openings through its outer wall affording access to said rotary connectors.

2. A binder comprising a clamping-member equipped with take-up mechanism and flexible posts connected with said take-up mechanism, said flexible posts having threaded connecting portions; and a companion

clamping-member equipped internally with bearings and threaded rotary connectors journalled and confined in said bearings, said connectors being provided with outer key-engaging ends, and said last-mentioned clamping-member having its outer wall provided with openings giving access to said rotary connectors and registering with said key-engaging ends.

3. In a binder, a hollow clamping-member having bearings therein and having its outer wall provided with perforations registering with said bearings, and rotary connectors journalled and confined in said bearings having actuating stems presented to said perforations.

4. In a binder: a hollow clamping-member having its outer wall provided with perforations; bearings secured in said clamping-member having bores extending therethrough provided at their outer portions with countersinks; rotary connectors journalled in said bearings, each comprising an internally threaded sleeve portion, an annular flange, and an angular shank; and washers confined between said flanges and the outer wall of said clamping-member.

5. In combination in a binder, a hollow clamping-member having take-up mechanism mounted therein, and having guides at its inner wall, flexible chain posts having portions within said clamping-member connected with said take-up mechanism and having portions extending through said guides and equipped at their free extremities with threaded members; and a companion clamping-member, having threaded rotary connectors journalled therein and adapted for connection with said chain posts, said last-mentioned clamping-member having key openings through its outer wall affording access to said rotary connectors, and said rotary connectors being provided with internally threaded sockets and with key-engaging shanks registering with said key openings.

6. In a binder, a hollow clamping-member having bearings therein and having its outer wall provided with perforations registering with said bearings, and rotary connectors equipped with annular flanges and journalled in said bearings, said connectors having actuating stems presented to said perforations, and said bearings having countersinks adapted to be engaged by the flanges of said rotary connectors, and spacing washers interposed between said flanges and the outer wall of the clamping-member.

7. In a binder, a metal clamping member having its outer and inner walls provided with openings, a U-shaped member housed within said clamping member and having openings therethrough aligned with the openings in said clamping member, a tubular member secured in said U-shaped member and having a bore extending therethrough

provided at its outer portion with a countersink, said tubular member having a reduced end adapted to engage one opening of said U-shaped member, a rotary connector journalled in said countersink and including an annular flange, an annular shank, and a washer confined between said flange and the outer wall of said clamping member.
